UNITED STATES PATENT OFFICE.

ALONZO J. MCMASTER, OF LOCKPORT, NEW YORK.

CAMPING-VEHICLE.

SPECIFICATION forming part of Letters Patent No. 404,101, dated May 28, 1889.

Application filed March 14, 1889. Serial No. 303,248. (No model.)

To all whom it may concern:

Be it known that I, ALONZO J. MCMASTER, a citizen of the United States, residing at Lockport, in the county of Niagara and State of New York, have invented certain new and useful Improvements in Camping Cars or Carriages; and I do hereby declare the following to be a full, clear, and exact description of the invention, such as will enable others skilled in the art to which it appertains to make and use the same, reference being had to the annexed drawings, forming a part of this my specification of said invention.

My invention consists of a camping-carriage the constituent parts of which are so constructed, combined, and arranged that all the furniture, bedding, and kitchen requirements for camping purposes are supplied in the most compact form, and the carriage capable of use at pleasure either as a sitting-room, bed-room, or kitchen.

In the accompanying drawings, Figure 1 is a perspective view of my camping-carriage equipped and ready for use. Fig. 2 is a detail front view, in perspective, of the carriage-body, showing the driver's seat turned down upon its hinges, exposing an oil-stove to view. Fig. 3 is a perspective view of a slop-bucket and its suspending mechanism. Fig. 4 is a perspective view of one of the inner front corners of the carriage, showing doors opening into the oil-stove chamber and into a wardrobe, and an ice-chamber with waste-pipe, and a tank for drinking-water. Fig. 5 is a rear view of the wardrobe-door provided with folding table-legs. Fig. 6 is a perspective view of a top or follower plate provided in the ice-box proper. Fig. 7 is a perspective view of the inner front corner of the carriage opposite the ice-chamber, showing a water-tank basin with spigot, drawer, and a portion of the upholstered seat. Fig. 8 is a perspective view of the seat and its back, the latter in position for use as a berth and provided with a safe-guard. Fig. 9 is a transverse vertical section of the basin shown in Fig. 7 and of a privy-seat and trap-door below. Fig. 10 is a horizontal section below the said basin and through the walls and door of the privy-chamber. Fig. 11 is a linear sketch of the carriage-seat and upper berth with guard and fastening. Fig. 12 is a modified construction of the

safeguard of the upper berth. Fig. 13 is a perspective view of the carriage-body provided with a fly or canvas protection, and Fig. 14 is a linear plan view of the inner carriage room and fixtures.

The letter A in the drawings represents the carriage-body, and B the wheels. A driver's seat, C, is provided at the front of the carriage, having a dash and foot board, c, a seat-box, c', and a seat proper, c'', attached to the box by means of hinges, c', so that the seat proper can be turned over forward in order to expose a coal-oil stove, c⁴, located in and securely fastened to the seat-box c'. This oil-stove can be reached through two doors, c⁵, in the front wall, a, of the carriage, so that a person in the carriage can easily attend to it. The top c⁸ of the box c' is provided with openings c⁶, through which the heat of the oil-stove passes in order to heat whatever pots or pans are placed above for cooking purposes. Such operations are generally performed within the carriage through two hinged windows, c⁷, in the front wall of the carriage; but the stove can also be easily removed from the box c' through the doors c⁵ and used outside the camp-wagon; or it may be moved on rollers or slides upon the floor, or upon rails or in grooves into the interior of the carriage, and there provided with the necessary guards, in order to use it for a warming-stove in cold weather.

The two inner corners at the front wall are occupied by an ice-chamber, D, and wash-basin E. The ice-chamber is provided with a metallic ice-box, d, and a top and follower, d', having upright corner-bearings d² with ball rollers d³, which latter roll along the inner corners of the ice-box d, and, being arranged in pairs, as shown in Fig. 6, keep the follower-plate in a level position while descending upon and with the melting ice.

On top of the ice-chamber a tank, d⁴, for drinking-water, with a spigot, d⁵, is provided, and a water-pipe, d⁶, arranged below said spigot, conveys the waste water down through the floor of the carriage to the ground below. An opening, d⁷, in the front wall of the carriage serves to facilitate the filling of the tank from the outside. Next to the ice-chamber D a wardrobe, F, with a door, f, is provided, the door f being removable from its

hinges f' , and having two pairs of ordinary folding legs, $f^2 f^3$, attached to its inner side, as shown in Fig. 5, by means of which said door, when removed from its hinges, may be 5 put upon its unfolded legs and used for a table. Between the wardrobe F and the rear wall of the carriage a seat, G, is provided, which is long enough for a full-grown person to lie upon conveniently for rest. Along the 10 side wall, a' , of the carriage an upholstered framed back, H, is provided for the convenience of persons using the seat G. The upper end portions of the back H are hung by means of diagonally-arranged links h to the 15 carriage, and are thus held in upright position with a thrusting action against the backs. When it is desired to move the back out of the way, it is turned up against the side wall of the carriage, and the links h will form its 20 lower support, while an ordinary bolt, h' , at each of the now elevated end portions will steady it in its position. When a sleeping-berth is desired above the seat G, the back H is turned into a horizontal position and 25 fastened by means of the said bolts to the carriage, the diagonally-arranged hinged links serving, in conjunction with said bolts, to hold it up firmly in said position; and it may be further secured against breaking 30 down by suspending the inner side from the top of the carriage by means of cords or links h^2 , the latter serving as bearers of a side slat, h^3 , or netting h^4 , whereby to prevent the inmate of the berth from falling out. 35

Opposite the ice-chamber D a wash-basin, E, is provided in a trap-door, e , which is hinged to a platform, j , of a drawer-chest, J, by means of hinges e^2 , arranged in a slightly diagonal axis, so that when turned up it will 40 move away from the side wall of the carriage, which is thus secured against scraping. A tank, e^3 , is placed upon the platform j ; and against the front wall, a , of the carriage, which is there provided with an opening, e^4 , in order to facilitate the filling of the tank from 45 the outside. This tank is, by means of a flexible pipe, e^5 , connected with a spigot, e^6 , at the side of the basin E, which by this means is provided with the necessary water. 50 Below the basin E, at a suitable elevation above the carriage-floor, is a privy-seat, I, which is closed by a vertically-hinged door, i . The door i is hung between the trap-door E and privy-seat I, and it opens and swings 55 inwardly only when the trap-door is turned up, as shown in dotted lines in Fig. 7, and then it is swung against the side wall, j' , of the drawer-chest J in the corner of the front wall, a . Below the privy-seat an inclined 60 trap-door, i' , is hung to the side wall, a^2 , of the carriage, and when the privy is to be used said trap-door is allowed to hang perpendicularly on its hinges, as the dotted lines in Fig. 9 indicate; and when the privy is not used 65 said trap-door is pulled by means of a cord,

i^2 , against the carriage-floor, and held there by fastening said cord to a button, i^3 , on the door i' . Below the trap-door i' a bucket, K, is hung to the carriage-floor, wherein the slop passing through a hole, a^3 , in the carriage-floor is received. The bail k of the bucket K is provided with two open loops, k' , which stand at right angles to the bail, and thus, when said loops are inserted into two eyebolts, k^2 , fastened to the carriage-floor, the weight of the bucket will cause the bail to be turned down against the side of the bucket, while by raising the bail the loops k' will slip out of the eyebolts k^2 and instantly disengage the bucket from the same. These loops k' are attached to eyebolts k^3 of 80 the bucket K, and by this construction the bucket can be suspended very closely to the carriage-floor, and not only will the bail be kept out of the way of the inflowing slop, but the bucket is also prevented from swinging about and splashing its contents while the wagon is moving; and, if desired, the bail K can be held in its position shown in Fig. 3 by a proper catch applied to the bucket. 85

The drawer-chest J contains a number of 90 drawers, j^2 , for the safe keeping of shoes and other articles of wear and of general use.

A partition-wall, i^4 , separates the basin and privy from a seat, G, and back H along the carriage side wall a , which seat and back are 95 exact counterparts to those above described along the opposite side wall a' . The side walls, $a' a^2$ are, provided with windows a^3 above the seat-backs H, and with windows a^4 in the rear wall, a^5 , and the door a^6 , through 100 which door steps a^7 facilitate an entrance into the vehicle.

Below the front portion of the carriage a tool-box, L, and an oil-reservoir, M, are fastened, and below the remaining portion of the carriage, on the side opposite the bucket K, a ladder, N, is suspended by means of hangers n and pins n' . This ladder, so suspended, will serve for stowing upon it harness, ropes, tents, and a fly or canopy. The tool-box L is 105 so fastened to the carriage that there is easy access to its contents—such as saws, axes, wrenches, hammers and nails, &c.—useful in case of breakage of the vehicle and other purposes. The oil-tank M will be so fastened to the floor of the carriage by means of adjusting screw-bolts and iron bands that it can be easily removed for the purpose of refilling. 115

While camping the ladder N will serve as a cot for the driver who has charge of the 120 camping-carriage at night.

The fly or canopy O will be used over the camping-carriage in hot or rainy weather as a protection for the more exposed parts of the carriage-body, and as a comfort to the inmates. The canopy O is stretched over diagonal stays o , hooked into eyes o' , provided on the carriage-body and held in position by guy-ropes o^2 , which are fastened to hooks o^3 on the carriage-body. Suitable drawers, g, may 130

also be provided under the seats G, to contain either fishing-tackle or additional household articles not mentioned above.

What I claim, and desire to secure by Letters 5 Patent, is—

1. In a camping-carriage, the combination of the swinging basin E, privy-seat I, and privy-door i, substantially as and for the purpose described.

10 2. In a camping-carriage, the combination of the driver's seat c², hinged at c³, seat-box c', oil-stove c⁴, windows c⁵, and doors c⁶, substantially as and for the purpose described.

15 3. In a camping-carriage, the combined arrangement of an ice-box, wardrobe, drawer-chest, wash-basin, privy, water-tanks, seats, and convertible sleeping-berths, substantially as described.

4. A camping-carriage having kitchen and

toilet accommodations, provided with a portable sleeping-cot ladder, and supports n n' for said ladder, said supports being constructed and arranged to permit the ladder to be adjusted beneath the carriage at a proper altitude for forming a sleeping-cot between the 25 ladder and the carriage-bottom, substantially as described.

5. A camping-carriage provided with a wardrobe having a portable door with folding table-legs attached to it, substantially as and 30 for the purpose described.

In testimony whereof I hereunto affix my signature in presence of two witnesses.
